UNITED STATES PATENT OFFICE.

DANIEL H. PETTINGELL, OF GOLCONDA, NEVADA.

RAIL-CHAIR.

1,187,087.

Specification of Letters Patent. Patented June 13, 1916.

Application filed March 28, 1916. Serial No. 87,258.

To all whom it may concern:

Be it known that I, DANIEL H. PETTINGELL, a citizen of the United States, residing at Golconda, in the county of Humboldt and State of Nevada, have invented a new and useful Rail-Chair, of which the following is a specification.

The present invention appertains to rail chairs, and aims to provide a novel and improved chair adapted especially for use in supporting a reversible double-ball rail.

It is the object of the invention to provide a chair for supporting in a thoroughly rigid and efficacious manner, a reversible double-ball rail, enabling the rail to be reversed, whereby to prolong the service thereof, in order that the rail will have a much longer life than an ordinary rail.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side elevation of the improved rail chair, used in joining the abutting ends of a pair of rails together. Fig. 2 is a side elevation illustrating a tie plate used in connection with the chair for supporting the rail. Fig. 3 is an enlarged vertical section taken on the line 3—3 of Fig. 1. Fig. 4 is an enlarged cross section taken on the line 4—4 of Fig. 2.

The rail chair is used as illustrated, for joining the adjacent ends of the rails R, each of which is reversible. Thus, each rail has the opposite balls or treads 1 connected by a web 2, and the rail is divided in a longitudinal median plane, as at D, to divide the balls and web, whereby to provide two similar longitudinal sections disposed side by side in reversed positions. In some instances, however, the rail need not be divided, and can constitute a unitary or integral part. With the divided rail, however, the two sections thereof can be reversed independent of one another, and the two sections can be interchanged.

The chair comprises a base plate 3 to rest upon the underlying ties 4 below the ad-

jacent ends of the rails, and this plate is provided adjacent one edge with spike openings 5 through which spikes 6 are driven into the ties, for securing the base plate 60 thereon. The plate 3 is provided at its other edge, which is at the outer side of the rail, with an upturned flange 7, while the plate 3 is provided between its edges with a longitudinal raised portion 8 parallel with 65 the longitudinal flange 7. The raised portion 8 provides a lower longitudinal recess 9, and the flange 7 and raised or upwardly offset portion 8 provide a longitudinal channel in which the lower ball 1 of the rail 70 is seatable snugly.

Integral with the upper edge of the flange 7 is an inclined brace 11 coextensive with the base plate 3, and having its lower edge lying in the same plane as the base 75 plate to rest upon the ties. Said lower edge of the brace 11 is provided with spike openings 12 through which spikes 13 are driven into the ties, for securing the brace 11 upon the ties. This brace 11 is preferably upon 80 the outer side of the rail, to resist the outward thrust imposed upon the rail. Integral with the upper edge of the brace 11 is an angle iron fish plate 10 adapted to fit one side of the web 2 upon the lower ball 1, said 85 fish plate 10 overhanging the channel formed by the flange 7 and raised portion 8.

An angle iron fish plate 14 which complements the fish plate 10, is adapted to fit the opposite side of the web 2 above the lower 90 ball 1, and has integral therewith an arcuate brace 15 coextensive in length with the base plate 3. The lower edge of the brace 15 rests upon the base plate 3 adjacent the spike openings 5, and said brace is spaced above 95 the raised portion 8. At the juncture of the fish plate 14 and brace 15, they are provided with a depending longitudinal wedge 16 coextensive in length with the fish plate and brace, and adapted to fit the respective side 100 of the lower ball 1, or to wedge between the lower ball and the raised portion 8, as seen in Fig. 3.

The fish plates 10 and 14 are provided with bolt openings 17, which are preferably 105 elongated vertically, and the web 2 of each rail has registering openings 18, clamping bolts 19 being engaged through the registering openings 17 and 18, to clamp the rails between the fish plates. Any suitable number of bolts 19 can be used, and these bolts simply clamp the parts together, and do not

receive any shearing strain, since the rail is adjustable vertically relative to the chair without subjecting the bolts 19 to a shearing strain. Nuts 20 are threaded upon the 5 bolts 19.

The raised portion 8 is provided with openings 21, registering or alining with openings or apertures 22 with which the brace 15 is provided between its edges, or 10 adjacent the wedge 16. Bolts 23 are inserted upwardly through the apertures 21 and 22, and have their heads seating in the recess 9, while nuts 24 are threaded upon the upper ends of the bolts 23, whereby to force the 15 brace 15 downwardly, so that its lower edge seats upon the base plate 3, while the wedge 16 is forced tightly between the lower ball 1 and the raised portion 8, thus clamping the lower ball or balls firmly within the channel 20 of the base plate. Thus, the web of the rail will not only be clamped between the fish plates, but the lower ball of the rail, which acts as the base thereof, will be clamped tightly in place through the medium of the 25 wedge 16.

When the inner section of the upper ball becomes worn out, the inner section of the rail can be turned upside down and turned end for end, to reverse it, thereby bringing 30 the unworn ball or tread section into place, thus renewing the serviceability of the rail, it being understood that the fish plates 14 and their braces 15 can be readily detached during the adjustments of the rails. The 35 wedges 16 will take up the wear of the lower ball 1. The two sections of the rail can also be interchanged, and each section can be reversed, so that all four ball or tread sections can be brought into position to receive the 40 wear due to the wheel flanges. The rail will therefore outlast several ordinary rails, and therefore renders greater service.

The tie plate which is used in connection with the chair for supporting the rail, is 45 designated at 25, and is provided adjacent its ends with spike openings 26 for the reception of spikes 27, and the tie plate has raised portions 28 for snugly holding the lower ball of the rail. The two sections of 50 the chair and the tie plate can be rolled.

forged, or otherwise manufactured. Said sections can be formed from plates of sheet metal which are doubled to provide the angular fish plates, as seen in Fig. 3.

Having thus described the invention, what 55 is claimed as new is:

1. A rail chair comprising a base plate having a channel for receiving the lower ball of a double-ball rail, said channel having a fish plate, and a complementing fish 60 plate having a wedge insertible into the channel.

2. A rail chair comprising a base plate having a channel for receiving the lower ball of a double-ball rail, said channel having a fish plate, a complementing fish plate 65 having a brace to rest upon the base plate, and having a wedge insertible into the channel, and means for securing said brace upon the base plate.

3. A rail chair comprising a base plate having an upturned flange at one edge, said flange having a fish plate, a base plate having a raised portion forming with said flange a channel for receiving the lower ball 75 of a double-ball rail, a complementing fish plate having a brace to rest upon the base plate, and having a wedge to fit between said ball and raised portion, and bolts connecting said raised portion and brace.

4. A rail chair comprising a base plate having an upturned flange at one edge, a brace and angle iron fish plate integral with the upper edge of said flange, a complementing angle iron fish plate having a brace to 85 rest upon the base plate, and having a wedge, the base plate having a raised portion forming with said flange a channel for receiving the lower ball of a double-ball rail, said wedge being adapted to fit between said 90 raised portion and ball, and bolts engaged through said raised portion and last mentioned brace.

In testimony that I claim the foregoing as my own, I have hereto affixed my signature 95 in the presence of two witnesses.

DANIEL H. PETTINGELL.
